MEANS FOR USE IN LASTING SHOES

William E. De Hart, St. Louis, Mo., assignor to
United Shoe Machinery Corporation, Paterson,
N. J., a corporation of New Jersey

Original application June 13, 1932, Serial No.
616,937. Divided and this application October
6, 1933, Serial No. 692,493. Renewed January
28, 1935

9 Claims. (Cl. 12—107)

This invention relates to means for use in lasting shoes, this application being a division of my copending application Serial No. 616,937, filed on June 13, 1932. An object of the invention is to provide improved means for holding shoe uppers in lasted position until extraneous holding means is no longer needed by reason, for example, of the setting or hardening of cement used in the lasting operation. The invention is herein illustrated by reference to the lasting of shoes of that type in which the margin of the upper is lasted in substantially parallel relation to the bottom of the last over an insole on the last, but it is to be understood that it is not limited to the manufacture of shoes of that particular type. In view of the applicability of the invention to the manufacture of shoes of different kinds, the term "sole" is frequently used hereinafter, especially in the claims, to designate generically the shoe bottom part over which the upper is lasted.

For the purposes in view the invention provides a novel device for holding an upper in lasted relation to a sole on a last, the device herein shown being constructed especially for use to hold the upper at the toe portion and rearwardly along the sides of the forepart substantially as far as the ball line. The device may thus be conveniently utilized, as illustrated, in lasting the entire forepart of the shoe with cement in a bed-lasting machine after the shoe has been lasted progressively along the shank portion by a machine that fastens the upper in lasted position by metallic fastenings, in accordance with the method disclosed and claimed in the above-mentioned copending application. More particularly, the upper-holding device herein shown comprises an upper-holding member formed to extend around the toe end of the shoe bottom over the margin of the sole, and other upper-holding members arranged to extend farther rearwardly along the sides of the shoe bottom and pivotally connected to the toe-holding member to swing widthwise of the shoe into upper-holding positions. The toe-holding member may be conveniently applied in proper relation to the toe portion of the upper and pressed down on the shoe bottom by use of the toe wipers of the bed-lasting machine while the other members are in idle positions where they do not interfere with that operation, after which the upper at the ball portion of the shoe may be properly tensioned, as by use of hand pincers first at one side of the shoe and then at the other side, and the rearwardly extending members may be swung in-

wardly and fastened at the opposite sides successively to hold the upper. As illustrated the different members are constructed for attachment to the shoe by fastenings driven into the shoe bottom to hold them in clamping relation to the upper, and if desired the toe-holding member may be thus fastened prior to the lasting of the upper at the ball of the shoe. The toe-holding member itself, as herein shown, is constructed substantially as disclosed in Letters Patent No. 1,894,678, granted on January 17, 1933 upon an application of Joseph Fausse, and the rearwardly extending pivoted members also embody features of that prior disclosure with reference especially to their cross-sectional outline and their provision for receiving fastenings that clamp them on the shoe. It is to be understood, however, that the invention is not limited to a construction of that particular character, nor limited to upper-holding means for use on the forepart of the shoe, since similar means may be used, if desired, at the heel end and shank portion of a shoe.

The novel features of the invention will now be more particularly described by reference to the accompanying drawing and pointed out in the claims.

In the drawing,

Fig. 1 is a perspective view illustrating how the upper-holding device provided by this invention may be utilized in the lasting of the forepart of a shoe in a bed-lasting machine;

Fig. 2 shows a portion of a shoe in side elevation with the upper-holding device thereon;

Fig. 3 is a plan view of the shoe after lasting; and

Fig. 4 is a perspective view of the novel upper-holding device detached.

A shoe on which the device is to be used may have been previously lasted along its shank portion and the upper fastened to the insole in that location by staples *s*, as more fully disclosed in the above-mentioned copending application, although it is to be understood that the utility of the invention is not dependent upon such prior treatment of the shoe. For the lasting of its forepart the shoe may be placed in a bed-lasting machine of a well-known type, as illustrated in Fig. 1, the machine having toe-embracing wipers *t* that are operated in the customary manner to wipe the marginal portion of the upper around the toe inwardly over the insole and to press it firmly down upon the insole. If the toe portion of the upper materials includes a lining and a box toe stiffener, the operator may first advance

and close the wipers to wipe all the different layers of the upper materials inwardly over the insole and may thereafter, in accordance with the usual practice in lasting toes with cement, retract the 5 wipers and trim the lining and the toe stiffener back substantially to the edge of the insole. He will then apply cement to the margin of the upper around the toe and may at the same time apply cement to the upper materials at the rear of the 10 toe portion substantially as far back as the ball line of the shoe. Alternatively, if cement has previously been applied at the forepart of the shoe for lasting purposes and has hardened, he will at this time apply a solvent to soften the 15 cement. The operator then preferably wipes the margin of the upper around the toe inwardly over the insole a second time and then retracts the wipers and applies to the shoe the novel upper-holding device constructed as shown in Fig. 4. 20 This upper-holding device comprises an upper-holding member 18 formed to extend around the toe end of the shoe bottom in engagement with the upper over the margin of the insole and provided with rearwardly extending arms for engaging 25 the upper along the opposite sides of the toe, and other upper-holding members 20 and 22 arranged to extend along the sides of the shoe bottom beyond these arms for engaging the upper substantially as far rearwardly as the ball line of 30 the shoe, the members 20 and 22 being pivotally connected respectively at 24 and 26 to the rear ends of the arms of the member 18 for swinging movements widthwise of the shoe to position them in proper relation to the shoe. The toe-holding member 18, as hereinbefore suggested, is constructed substantially as disclosed in the previously mentioned Letters Patent No. 1,894,678 and is provided with a portion 28 for engaging the upper in substantially parallel relation to the bottom face of the last and with an upstanding flange portion 30 inclined somewhat outwardly over the portion 28. The two angularly related portions 28 and 30 of the member 18 are thus arranged to be engaged by the wipers 16 of the lasting machine 40 in the manner illustrated in Fig. 1 to position the member in proper relation to the toe and to press it firmly down upon the shoe bottom. Also substantially as disclosed in the above-mentioned Letters Patent, there are provided in the portion 28 of the member 18 holes 32 arranged to receive tacks *t* driven into the shoe bottom close to the edges of the wipers, and the upstanding flange 30 is provided with offset portions 34 arranged to 45 present recesses in alignment with the holes 32 for the shanks of the tacks and curved upper edges to be engaged by portions of the heads of the tacks to hold the member clamped down upon the shoe bottom. It will be understood that the tacks are driven in the positions shown in Fig. 1 while the member 18 is held by the wipers in pressure-applying relation to the upper, and these tacks may, as illustrated, be driven prior to the lasting of the upper between the rear end of the toe portion and the ball line. 50 While the toe-holding member 18 is being applied and fastened to the shoe as above described, the members 20 and 22 are preferably in idle positions where they do not interfere in any way with the placing of the member 18 upon the toe, 55 as shown in Fig. 1. After the lasting of the toe the operator, by the use of lasting pincers 36, tensions the upper between the toe portion and the ball line at one side of the shoe in the manner illustrated in Fig. 1, and while holding the upper 60 under more or less tension by the pincers swings the appropriate upper-holding member (as shown, the member 22) inwardly over the margin of the insole, the pincers being removed prior to the completion of the inward movement of this member. It will be evident that the member 22 thus has some wiping action on the margin of the upper as it is moved into upper-holding position. Thereafter, while holding the member 22 pressed down upon the upper with one hand, the operator drives a tack or tacks *t* to fasten this member in 65 upper-holding position in the same manner as the toe-holding member 18, the members 20 and 22 in the construction shown having angularly related portions 28' and 30' and also tack holes 32' and offsets 34' substantially like the corresponding portions of the member 18. After thus lasting the shoe at one side substantially from the rear end of the lasted toe portion to the portion previously lasted with staples, the operator similarly lasts the corresponding portion at the opposite side of the shoe, applying and fastening the upper-holding member 20 in the same manner as the member 22. The operator then lasts the heel end of the shoe in any desired manner, Fig. 3 illustrating the use of tacks to hold the upper at the 70 heel seat, and thereafter removes the shoe from the bed-lasting machine. After the cement used to fasten the forepart of the upper in lasted position has substantially hardened, the upper-holding device applied as described in the lasting operation is removed from the shoe. 75 It will be observed that the upper-holding members 20 and 22 in the construction shown are curved somewhat widthwise of the shoe in substantial accordance with the curvature of the 75 edge of the portions of the shoe bottom along which these members extend. As illustrated the members 20 and 22 present substantially flat upper-engaging faces in the same plane as the upper-engaging face of the toe-holding member 18 for use on shoes the bottoms of which are substantially flat at the forepart. It will be understood, however, that for use on shoes the bottoms of which are differently shaped the members 20 and 22 may be curved somewhat heightwise of the 80 shoe to correspond to the curvature of the shoe bottom. 85 The illustrated upper-holding device applied and fastened as above described maintains firm pressure on the upper over the greater portion of the width of its lasting margin, not only around the toe portion of the shoe bottom but also substantially as far rearwardly as the ball line, thus insuring that the upper will be securely fastened to the insole by the cement all along the margin 90 of the shoe bottom throughout substantially the entire length of the forepart and also, by the compacting pressure applied to the upper, preparing this portion of the shoe bottom in a very satisfactory manner for later manufacturing operations. It will further be evident that in lasting the forepart rearwardly to the ball line in the manner described, with the use of means to clamp the upper firmly upon the insole to hold it until the cement has set, pyroxylin cement may well be 95 utilized to fasten the upper rearwardly to the ball line as well as around the toe, with such advantages as there may be in the use of cement of that character for some kinds of work as compared with rubber cement customarily used in 100 lasting progressively with the side-lasting machine.

Having described the invention, what I claim as new and desire to secure by Letters Patent of the United States is:

1. A device for holding an upper in lasted relation to a sole on a last, said device comprising an upper-holding portion formed to extend around an end of the shoe bottom over the margin of the sole, and other upper-holding portions arranged to extend along the sides of the shoe bottom beyond said first-mentioned portion and movable relatively to the latter widthwise of the shoe to position them in proper relation to the shoe, the device being portable with the shoe while holding the upper in lasted position.

2. A device for holding an upper in lasted relation to a sole on a last, said device comprising an upper-holding portion formed to extend around an end of the shoe bottom over the margin of the sole, and other upper-holding portions arranged to extend along the sides of the shoe bottom beyond said first-mentioned portion and pivoted to the latter for swinging movements widthwise of the shoe to position them in proper relation to the shoe, the device being portable with the shoe while holding the upper in lasted position.

3. A device for holding an upper in lasted relation to a sole on a last, said device comprising an upper-holding portion formed to extend around an end of the shoe bottom over the margin of the sole, and other upper-holding portions arranged to extend along the sides of the shoe bottom beyond said first-mentioned portion and movable relatively to the latter widthwise of the shoe to position them in proper relation to the shoe, said different portions being constructed for attachment to the shoe by fastening means penetrating the sole to hold the device in clamping relation to the upper.

4. A device for holding an upper in lasted relation to a sole on a last, said device comprising an upper-holding member formed to extend around an end of the shoe bottom over the margin of the sole and having arms for engaging the upper along the opposite sides of the shoe bottom, and other upper-holding members arranged to extend along the sides of the shoe bottom beyond said arms and hinged to the arms for swinging movements widthwise of the shoe to position them in proper relation to the shoe, the different members having openings therein to receive fastenings driven into the shoe bottom to maintain them in upper-holding positions.

5. A device for holding an upper in lasted relation to a sole on a last, said device comprising an upper-holding member formed to extend around the toe end of the shoe bottom over the margin of the sole, and other upper-holding members arranged to extend along the sides of the shoe bottom substantially as far as the ball line of the shoe and connected to said first-mentioned member to swing relatively to the latter widthwise of the shoe into upper-holding posi-

tions, the device being portable with the shoe while holding the upper in lasted position.

6. A device for holding an upper in lasted relation to a sole on a last, said device comprising an upper-holding member formed to extend around the toe end of the shoe bottom over the margin of the sole, and other upper-holding members arranged to extend along the sides of the shoe bottom substantially as far as the ball line of the shoe and connected to said first-mentioned member to swing relatively to the latter widthwise of the shoe into upper-holding positions, each of said members having one or more openings therein to receive fastening means driven into the shoe bottom to hold the device in clamping relation to the upper.

7. A device for holding an upper in lasted relation to a sole on a last, said device comprising an upper-holding member formed to extend around the toe end of the shoe bottom over the margin of the sole, and other upper-holding members arranged to extend along the sides of the shoe bottom at the ball of the shoe and connected to said first-mentioned member for swinging movements widthwise of the shoe, said other members being curved widthwise of the shoe substantially in accordance with the curvature of the edge of the shoe bottom along the ball of the shoe.

8. A device for holding an upper in lasted relation to a sole on a last, said device comprising an upper-holding member formed to extend around an end of the shoe bottom over the margin of the sole, and other upper-holding members arranged to extend along the sides of the shoe bottom beyond said first-mentioned member and hinged to the latter for swinging movements widthwise of the shoe to position them in proper relation to the shoe, each of said members being angular in cross section to provide an upper-engaging portion in substantially parallel relation to the bottom of the last and an upstanding flange and being constructed for attachment to the shoe by fastening means penetrating the sole.

9. A device for holding an upper in lasted relation to a sole on a last, said device comprising an upper-holding member formed to extend around an end of the shoe bottom over the margin of the sole, and other upper-holding members arranged to extend along the sides of the shoe bottom beyond said first-mentioned member and hinged to the latter for swinging movements widthwise of the shoe, each of said members having a portion arranged to face the bottom of the last and provided with one or more openings to receive tacks driven into the shoe bottom and having also an upstanding flange provided with one or more offset portions presenting recesses for the shanks of the tacks and curved seats for the heads of the tacks.

WILLIAM E. DE HART.
